[57] CLAIM

The ornamental design for a combined electric drill and screwdriver, as shown and described.

DESCRIPTION

FIG. 1 is a right side elevational view of a combined electric drill and screwdriver showing our new design; FIG. 2 is a top plan view thereof;

FIG. 3 is a right plan view thereof;

FIG. 4 is a bottom plan view thereof;

FIG. 5 is a front elevational view thereof;

FIG. 6 is a rear elevational view thereof;

FIG. 7 is a vertical cross-sectional view thereof, taken along line 7—7 of FIG. 3; and

FIG. 8 is a horizontal cross-sectional view thereof, taken in the direction of line 8—8 of FIG. 1.
